TYPEWRITER COMPANY, OF NEW YORK, N. Y., A CORPORATION OF DELAWARE.

MULTIPLE-BELLOWS PUMP.

1,307,459.

Specification of Letters Patent. Patented June 24, 1919.

Original application filed May 24, 1916, Serial No. 99,488. Divided and this application filed August 16, 1917. Serial No. 186,478.

To all whom it may concern:

Be it known that I, LYMAN R. ROBERTS, a citizen of the United States, residing in Rutherford, in the county of Bergen and 5 State of New Jersey, have invented certain new and useful Improvements in Multiple-Bellows Pumps, of which the following is a specification.

This invention relates to an improvement 10 in engines, etc., particularly in air pump mechanism, and is a division of my application No. 99,488, filed May 24, 1916 (now Patent No. 1,247,151, dated November 20, 1917).

15 For the purpose of obtaining a steady suction so as to operate pneumatic mechanism as in my application above-mentioned, a multiple unit pump is used. This is in the form of a bellows motor having three suction sections with a common storage section. 20 The individual suction sections are driven from a common shaft and in a regular sequence, so as to obtain a continuous suction action, and thereby maintain a constant 25 vacuum in the so-called storage section.

The connection from the drive shaft to the suction sections is of a novel type, to give a noiseless action and with a minimum of friction. This includes a plurality of eccen- 30 trics, one for each suction section, and having their centers located on lines radiating from the common axis about which they rotate, preferably at 120° from each other. The eccentrics are connected to the bellows

35 of the individual suction sections by bands or endless connections, which pass around the eccentrics and around the pulleys on the suction sections in the manner of pulley drives. The action, however, is that of an

40 eccentric rather than that of a pulley drive, the flexible connection traveling and rotating the pulleys idly, so as to make a smooth driving connection. The flexible connections are maintained taut, and the action of 45 the eccentrics opposed, by springs connected to the bellows sections.

Other features and advantages will hereinafter appear.

In the accompanying drawings,

50 Figure 1 is a perspective view.

Fig. 2 is a side view in elevation looking from left to right in Fig. 1.

The motor 1 is provided with a shaft 2, to which is secured a worm 3, driving a

worm wheel 4 secured to a shaft 5. The 55 shaft 5, by means of gearing indicated in general at 6, operates mechanism of the pneumatic typewriter actuator, as explained more fully in my above-mentioned applica- 60 tion. The shaft 5 also drives a vacuum pump 7, so as to furnish the suction necessary to operate the various pneumatic actuators of the typewriter operator. The vacuum pump 7 includes a storage section or

chamber 8, which is common to three active 65 suction sections 9, 10 and 11. The storage section 8 is separated from the suction sections 9 to 11 by a partition (not shown) with separate valve passages. This ar- 70

angement is such that each of the sections 9 to 11 will tend to draw out the air from the storage section 8 and maintain the latter under a constant vacuum. The action of this vacuum is opposed by a spring 12, so that when any pneumatic actuator of the 75 typewriter operator is connected to the section 8, in a manner more particularly explained in my above-mentioned application, the air will be withdrawn from the pneu- 80

matic actuator, so as to cause an action of the same. Both the storage section 8 and the pumping sections 9 to 11 are in the form of bellows having fixed and movable sides hinged together and connected by the usual accordion plaiting. The movable sides of 85 the sections 9 to 11 are normal under a tendency to collapse by means of individual springs 13.

The active pumping sections 9 to 11 are 90 driven from the shaft 5, so as to operate in rotation, thereby causing a constant withdrawal of the air from the storage section 8. This driving mechanism includes a plurality of eccentrics 14, 15 and 16, one for each of the sections 9 to 11. These eccentrics 95 are staggered relatively to each other, so that they will have their maximum torque at equally spaced intervals as to the rotation of the shaft 5. That is to say the centers of the eccentrics are located on lines radiating from the axis of the shaft 5, which lines are arranged at angles 120° from each other.

The eccentrics 14 to 16 are in the form of pulleys, which may be stamped out of sheet metal and are connected to pulleys 17, 18 105 and 19 on the active sections 9 to 11 by means of endless flexible connections, shown in the form of chains 20 to 22. The endless

connections 20 to 22, while they travel in the manner of driving pulleys, are in reality flexible eccentric rods and eccentric straps combined. The flexible connections 20 to 22 are maintained taut by the springs 13, which also return the suction sections to a collapsed condition. This driving arrangement of the suction sections is noiseless, and has the friction reduced to a minimum.

10 The action of the device is readily understood when taken in connection with the above description. The pump 7 proper is provided with the usual valves and passages, so that as each of the sections 9 to 11 collapses under the pull of its associated spring 13, it forces out the air previously withdrawn from the common vacuum chamber or section 8. This section 8 is connected to the sections 9 to 11 by individual passages and valves and acts as a storage of vacuum. In other words, it provides an inclosed space or chamber having less air pressure than the space surrounding the chamber. This enables the air to be withdrawn from any part connected to the storage section 8.

The sections 9 to 11, being driven in rotation, provide a constant suction on the section 8, as they are connected individually thereto with the usual passages and valves. This is provided for by the drives from the shaft 5 to the sections 9 to 11 which act in regular sequence, due to the regular spacing of the eccentricities 14 to 16 around the shaft 5 preferably at angles of 120° from each other. By combining the eccentric, strap and connected roller in one continuous flexible member, the friction is reduced and also the noise.

Variations may be resorted to within the scope of the invention, and portions of the improvements may be used without others.

Having thus described my invention, I claim:

1. The combination with a pneumatic pump having a plurality of pumping elements, each provided with a pulley, of a drive shaft for said elements, eccentricities mounted on said shaft, endless flexible connections running over said eccentricities and said pulleys and thereby driving said pumping elements, and springs individual to said elements maintaining said flexible connections taut.

2. The combination with a pneumatic pump, of a shaft for driving said pump, an eccentric pulley mounted on said shaft, a pulley connected to said pump, an endless

flexible connection wrapping around said pulleys and connecting them in driving relation, and means to maintain the flexible connection taut.

3. The combination with a vacuum pump, of a shaft for driving said pump, continuously traveling endless flexible reciprocating connections between said shaft and said pump, for enabling said shaft to actuate said pump, and means for maintaining the connections taut.

4. The combination with a pneumatic pump including a plurality of individually-operable sections, a shaft for driving said pump, and individual driving connections between said shaft and each of said sections, said driving connections being staggered relatively to each other, so as to afford a regular continued action of said sections, each of said driving connections including a continuously traveling flexible endless element enabling the rotary movement of said shaft to operate said sections, and means to maintain said endless elements taut.

5. The combination with a pneumatic pump having three separately-operable sections, of a shaft for driving said pump, a plurality of eccentric pulleys secured on said shaft at angles of 120° to each other, so as to be evenly distributed around said shaft, an idle pulley connected to each of said pump sections, and an endless connection wrapped around each of said pairs of idle and eccentric pulleys, so as to form combined traveling and reciprocating driving connections between the shaft and the pump sections.

6. The combination with a pneumatic pump having three separately-operable sections, of a shaft for driving said pump, a plurality of eccentric pulleys secured on said shaft at angles of 120° to each other, so as to be evenly distributed around said shaft, an idle pulley connected to each of said pump sections, an endless connection wrapped around each of said pairs of idle and eccentric pulleys, so as to form combined traveling and reciprocating driving connections between the shaft and the pump sections, and a spring individual to each of said pump sections for opposing the action of the associated eccentric and maintaining the associated flexible connection taut.

LYMAN R. ROBERTS.
